UNITED STATES PATENT OFFICE

BOLIVER MARGWARTH, OF NEWPORT BEACH, CALIFORNIA

PRINTING-PRESS ATTACHMENT

Application filed June 25, 1928. Serial No. 288,032.

My invention relates to improvements in printing press attachments, and it consists in the combinations, constructions and arrangements hereinafter described and claimed.

5 In the Miehle vertical press, the feeder table supports a large pile of stock ready for feeding, and this stock has the upper sheets thereof kept slightly separated from each other by a jet of air which is directed against 10 the edges of the sheets. Suction shoes carried by the separator frame lift the uppermost sheets one at a time from the stock and convey them to the printing mechanism. These shoes press down upon the upper sheets 15 and expel the layers of air between the sheets, thus causing at certain times more than one sheet to be removed from the stock by the suction shoes.

The purpose of the present invention is to 20 prevent the suction shoes from actually bearing weight on the uppermost sheet and pressing the sheet down upon the next sheet. In this way the layer of air between the two uppermost sheets will not be disturbed, and 25 the shoes will remove only one sheet at a time from the stock.

The invention consists of a simple attachment which is designed for the Miehle printing press, but it is obvious that the device 30 may be changed slightly to fit presses of other constructions. The purpose of the device is to prevent the suction shoes from pressing down the uppermost sheet of paper.

Other objects and advantages will appear 35 in the following specification, and the novel features of the device will be particularly pointed out in the appended claims.

40 My invention is illustrated in the accompanying drawing forming a part of this application, in which

Figure 1 is a sectional view through a portion of the Miehle printing press showing my attachment operatively applied thereto;

45 Figure 2 is a top plan view of the attachment;

Figure 3 is a longitudinal section through the device; and

Figure 4 is a perspective view of the bracket.

50 In carrying out my invention, I make use

of a feeder table 1 that is automatically raised by a rod 2 as the stock 3 carried by the table is being depleted. Feeder arms 4 carrying suction shoes 5 move from the stock 3 to the printing portion of the press, not shown. An air jet 6 directs air against the front edges of the uppermost sheets of the stock and keeps these upper sheets separated from each other by layers of air.

The shoes 5 are carried by a separator 60 frame 7, and the frame is prevented from allowing the shoes to rest upon the upper sheet by an arm 8 (see Figure 2) that has a platform 9 bearing against the frame 7. The arm is held in a position to dispose the shoes 65 5 above the upper sheet, and this is accomplished by an adjustable foot 10 that is movable along the arm 8 and is secured in adjusted position by means of a set screw 11.

The end of the arm 8 opposite to that of the 70 platform 9 is threaded as at 12 and carries lock nuts 13. The threaded portion is received in opening 24 in bracket 25. The bracket 25 is secured to a cross rod 14 by means of a clamp 17.

75 From the foregoing description of the various parts of the device, the operation thereof may be readily understood.

During the normal operation of the machine, the arms 4 swing back and forth carrying a sheet each time they swing to the left when looking at Figure 1. The frame 7 and the shoes 5 are carried by the arms. Each time the arms 4 come to rest at the extreme right of their swing, the frame 7 is supported 80 by the platform 9 in a position to prevent the shoes from actually putting pressure on the uppermost sheet. Of course, suction is being applied to the shoes at all times by means of the flexible pipes 15 which communicate with 85 a suction pipe 16. The upper sheets are separated from each other by the air flowing through the air jet 6. There will therefore be a layer of air between the two uppermost sheets, and when the shoes come in contact 90 with the uppermost sheet, it will not carry the sheet disposed therebeneath. This simple expedient permits only one sheet to be fed to the press at a time.

95 The weight of the shoes, instead of being 100

carried by the front edges of the uppermost sheets, is carried by the foot 10 which rests upon the stock. This foot is spaced far enough away from the front to permit the 5 front edges to be kept separated from each other by the air flowing from the pipe 6.

The device is also adapted to handle envelopes. The distance the shoes go down governs the automatic raising of the pile of 10 paper. As envelopes are soft and fluffy, the shoes bear so heavily upon them that the stack of envelopes keeps on raising clear out of the holder. With my invention the bar 10 takes up the pressure and the envelopes 15 do not come up too high. As the pile lowers, so do the bar 10 and the shoes. Consequently, the automatic lifter (not shown) starts to operate and raises the envelopes and bar 10. With the handling of envelopes, the 20 bar 10 has more surface than the two shoes, consequently the pressure is distributed over more surface. The invention is very important in both uses. Envelopes cannot be fed at all on the standard Miehle press now. 25 Although I have shown and described one embodiment of my invention, it is to be understood that the same is susceptible of various changes, and I reserve the right to employ such changes as may come within the 30 scope of the appended claims.

I claim:

1. A device of the type described comprising an arm, a platform carried by one end of said arm, and a foot adjustable on said 25 arm.

2. A device of the type described comprising an arm, a platform carried by one end of said arm, and a foot adjustable on said arm, the opposite end of said arm being 40 threaded and carrying a lock nut.

3. The combination with a printing press of the vertical type having a stock-carrying feeder table, suction shoes, and arms for moving said shoes to and from said stock, of a stationary arm for supporting said shoes and for spacing them from said stock, and a foot 45 adjustably secured to said arm and bearing against the stock.

4. The combination with a printing press 50 having suction shoes for removing one sheet at a time from the stock, of a stationary arm for supporting said shoes and for spacing them from the stock, and a member carried by said arm and transversely bearing against 55 the stock, said member being disposed rearwardly of said shoes.

5. The combination with a printing press 60 having a stock-carrying table, suction shoes, and means for moving said shoes to and from the stock, of a stationary arm for supporting said shoes and for spacing them from the stock, and a laterally-extending member carried by said stationary arm and being adjustable along the length of said arm, said 65 member bearing against said stock.

6. The combination with a printing press having a stock-carrying table, suction shoes, and means for moving said shoes to and from the stock, of a stationary arm for supporting said shoes and for spacing them from the stock, a laterally-extending member carried by said stationary arm and being adjustable along the length of said arm, said member bearing against the stock, and means for swinging said transverse member into parallelism with the plane of the stock.

70 San Francisco, Calif., May 4, 1928.
